UNITED STATES PATENT OFFICE

96,923

DESIGN FOR A BAR BACK COUNTER OR SIMILAR ARTICLE

Aaron Lebensonfeld, Brooklyn, N. Y.

Application June 29, 1935, Serial No. 57,460

Term of patent 14 years

To all whom it may concern:

Be it known that Aaron Lebensonfeld, a citizen of the United States and resident of Brooklyn, in the county of Kings and State of New York has invented a new, original, and ornamental Design for a Bar Back Counter or Similar Article, of which the following is a specification, reference being had to the accompanying drawing, forming part thereof, in which,

The figure is a perspective view of a bar back counter or similar article embodying my new design, the end not shown being like the end shown in the drawing.

I claim:

The ornamental design for a bar back counter or similar article, substantially as shown and described.

Dated, New York city, N. Y., June 20th, 1935.

AARON LEBENSONFELD.
